Mich., a corporation of Delaware
Filed July 10, 1962, Ser. No. 208,695
11 Claims. (Cl. 200—61.34)

This invention relates to a switch and more particularly to a switch adaptable for use in vehicle direction signals.

An aim of this invention is to provide a simple, reliable and compact switch. This switch may be readily installed in a vehicle direction turn signal actuator, although the invention is not limited to that particular application. Another aim of the invention is to provide a switch having a plurality of movable and stationary contacts all mounted on a single insulating base member.

The invention is carried out by providing a base of insulating material with a plurality of stationary contacts and flexible contacts mounted thereon and providing an actuator means for moving at least one of the flexible contacts into selective engagement or disengagement with at least some of the other contacts. The invention is further carried out by providing a switch base of insulating material, a plurality of stationary contact members mounted on the base, a first flexible contact engaging one of the stationary contact members, and a pair of additional flexible contacts each in engagement with a stationary contact member and both in engagement with a common stationary contact member, and actuator means for effecting selective movement of one of the pair of flexible contacts away from the common stationary contact into engagement with the first flexible contact and another stationary contact.

The above and other advantages will be made more apparent from the following specification taken in conjunction with the accompanying drawing in which:

FIGURE 1 is a partly broken away top view of a direction signal actuator containing a switch constructed according to the invention;

FIGURE 2 is a partly broken away side view of FIGURE 1;

FIGURES 3 and 4 are top views of the switch according to the invention; and

FIGURE 5 is a bottom view of the switch according to the invention.

Referring now to FIGURES 1 and 2, direction signal housing 10 is adapted to be mounted on a vehicle steering column by conventional means, not shown. Located within the housing 10 is a turn signal actuator mechanism comprising a molded plastic support portion 12 secured to the housing 10 by three screws 14 and a molded plastic crescent-shaped actuator 16 pivotally mounted on the support portion 12.

The molded actuator 16 includes a crescent-shaped body having a downwardly extending integral pivot pin 18 at its center and a groove 20 near the pivot pin for receiving the direction signal lever 22. A screw 24 secures the lever to the body. The pivot pin 18 seats in a bore 21 in the support portion 12 and is secured therein by a screw and washer assembly 23. Each end of the crescent-shaped body carries an inwardly turned pawl 26 attached to the body by a thin resilient section 28. A yieldable stiffening finger 30 is spaced from and located inside each pawl. The pawls are arranged so that when the actuator is in its neutral position both pawls will be clear of a canceling cam, not shown, on the steering wheel. However, when the actuator is pivoted to the right or left, one of the pawls will be in the path of the canceling cam. When the steering wheel is rotated in the direction of the

indicated turn, the canceling cam will touch the interfering pawl and move it aside momentarily, but will not change the position of the actuator. When the steering wheel is rotated in the other direction the cam will contact the pawl 26 and push it against the stiffening finger 28. Then the pawl will move no further with respect to the actuator and the entire actuator will be forced back to neutral position by the canceling cam. If, for some reason, the actuating plate becomes jammed and cannot move, then the stiffening finger 28 and the pawl 26 will yield so that continued rotation of the steering wheel will be permitted. Each end of the crescent-shaped body also carries a depending detent cam 32 which engages an undulated detent spring 34 on the support portion 12. When the actuating plate is in neutral position, each detent cam 32 will seat in the outer portion of the corresponding detent spring 34 and will be held in that position until the direction signal lever 22 is moved manually. When the actuator is moved each cam 32 will likewise be moved to the right or left of the neutral position on the detent spring and will be held in its new position until the actuating plate is returned to neutral either manually or by the canceling action described above.

The support portion 12 contains a generally rectangular opening 40 which supports a switch 42. The actuator 16 has a depending switch actuator finger 44 integrally molded thereto. The actuator finger 44 extends into the opening 40 to operate the switch 42 when the actuator member 16 is rocked about its pivot axis.

As best shown in FIGURE 3, the switch 42 comprises a base 46 of insulating material, preferably molded plastic, having an upper surface 48, a well portion 50, a pair of upwardly projecting integral pins or lugs 52, and an upwardly projecting integral rectangular block or lug 54.

Molded into the base 46 are six metallic stationary contacts 56-66 in the form of circular pins. Contacts 56 and 58 are disposed on either side of the well 50. Contacts 60 and 62 are disposed at one end of the well on the center line of the switch while the fixed contacts 64 and 66 are disposed on either side of the switch center line but close to the contacts 60 and 62. Each of the contacts is secured to an insulated conductor 68. The several conductors 68, as shown in FIGURE 5, are molded in the base material and are so arranged as to emerge from the base equally spaced and in line. A pair of flexible J-shaped spring contacts 70 and 72 are mounted on the switch base by having their ends 74 and 76, respectively, partially curled around the pins 56 and 58, respectively, while each loop portion of the J-shaped springs 55 abuts the rectangular lug 54. The long leg 78 or 80 of each J-shaped contact is flexible and is resiliently biased into electrical contact or conductive engagement with a common stationary contact 60. The extreme ends 79 and 81 of the flexible legs 78 and 80, respectively, are corrugated or otherwise formed into suitable contact surfaces. A C-shaped flexible spring contact 82 having outwardly curled ends 84 and 86 is supported on the switch base 46 by being wrapped around insulating lugs 52 and the stationary contact 62. To assure good electrical contact between C-shaped spring contact 82 and stationary contact 62, a leaf spring 88 has its ends supported against an end wall 89 of opening 40 of the support portion 12 and has its central portion engaging the spring contact 82 to force it against stationary contact 62. It should further be noted that the contact pins 64 and 66 are also close to the legs 78 and 80 but that they are spaced further from the legs 78 and 80 than are the curled portions 84 and 86 of the contact 82. The actuator finger 44 which depends from the actuator 16 extends into the well 50 of the switch base and lies between the J-shaped spring contacts 70 and 72.

In operation, when the actuator 16 is rocked about its pivot axis the actuator finger 44 moves within the well 50 into engagement with either the leg 78 or leg 80 of the J-shaped contacts. If the actuator finger 44 moves upwardly, as shown in FIGURE 4, it will engage the flexible leg 78 to move it away from contact pin 60 and then will cause engagement of leg 78 with end 84 of the spring contact 82, and subsequently, upon further movement will come into engagement with stationary contact 64. During this further movement the upper end of the spring 82 flexes to the extent that it becomes disengaged from the lug 52. This flexing movement of spring 82 assures that the flexible leg 78 can move far enough to engage contact 64 and thereby avoids the problem of hanging up, which occurs when it is attempted to cause one flexible contact to bridge two stationary contacts. In the latter case it is not uncommon for the flexible contact to make a good connection with one stationary contact but to make a poor connection or no connection with the other. If the actuator finger 44 is moved downwardly it will effect a similar movement of flexible leg 80 of contact 72 to break its connection with contact 60 and to make a connection first with end 86 of spring contact 82, and subsequently, with stationary contact 66.

When the switch is to be used in a vehicle direction signal it should be connected to the vehicle light circuits (not shown) as follows: stationary contacts 56, 58 are connected to right and left stop lamps; contact 60 is connected to a brake switch; contact 62 is connected to a direction signal flasher; and contacts 64 and 66 are connected to right and left front turn indicator lamps, respectively. Thus when the switch is in neutral position and the vehicle brakes are applied, a brake switch will be closed to energize contact 60 and hence energize both stop lamps through spring contacts 70, 72 and contacts 56, 58. However, when the actuator 16 is moved to its right turn operative position and the actuator finger 44 moves upwardly as shown in FIGURE 4, then the connection between the right stop lamp and the contact 60 is broken and instead, the stop lamp is connected through contact 56, spring contact 70 and spring contact 82 to the flasher contact 62 thereby causing flashing of the right stop lamp due to the intermittent energization of contact 62 by the flasher. At the same time, due to the connection of contact 64 to spring contact 70, the right front indicator lamp will also flash. It should be noted, however, that when the switch actuator finger moves to operative position the flexible leg 78 engages the spring contact 82 prior to making a connection with contact 64. Hence the full load of the signal light system is not placed upon the flasher at one instant; rather, the load on the flasher is increased gradually. This is particularly important in this specific application because when the signal lamp filaments are cold they have a very low resistance and draw a large load current.

It will readily be seen that this invention provides a simple, reliable and compact switch particularly suitable for installation in a direction signal actuator but useful in other applications as well.

The embodiment of the invention described herein is for purposes of illustration and the scope of the invention is intended to be limited only by the following claims.

We claim:

1. A switch comprising a base of insulating material, a plurality of stationary contact members mounted on the base, a first flexible contact mounted on the base in conductive engagement with a first stationary contact member, a second flexible contact mounted on the base, a fixed contact member closely spaced from the second flexible contact, and actuator means movable into engagement with the second flexible contact for moving the second flexible contact into conductive engagement with the first flexible contact and the fixed contact member.

2. A switch comprising a base of insulating material, a plurality of stationary contact members mounted on the base, a first flexible contact mounted on the base in conductive engagement with a first stationary contact member, a second flexible contact mounted on the base in conductive engagement with a second stationary contact member, a fixed contact member closely spaced from the second flexible contact, and actuator means movable into engagement with the second flexible contact into conductive engagement with the first flexible contact and the fixed contact member.

3. A switch comprising a base of insulating material, a plurality of stationary contact members mounted on the base, a first flexible contact mounted on the base in conductive engagement with a first stationary contact member, a second flexible contact member mounted on the base in conductive engagement with a second stationary contact member and closely spaced from the first flexible contact, a fixed contact member spaced from the second flexible contact member and further therefrom than is the first flexible contact, and actuator means movable into engagement with the second flexible contact for moving the second flexible contact into conductive engagement with the first flexible contact and subsequently with the fixed contact member.

4. A switch comprising a base of insulating material, a plurality of stationary contact members mounted on the base, a first flexible contact mounted on the base in conductive engagement with a first stationary contact member, a second flexible contact mounted on the base in rigid engagement with a second stationary contact member and resiliently biased into conductive engagement with another stationary contact member, and actuator means movable into engagement with the second flexible contact for moving the second flexible contact away from the said another stationary contact member and into conductive engagement with the first flexible contact.

5. A switch comprising a base of insulating material, a plurality of stationary contact members mounted on the base, a first flexible contact mounted on the base in conductive engagement with a first stationary contact member, a second flexible contact having a portion thereof fixedly mounted on the base and another portion thereof resiliently biased into conductive engagement with another stationary contact member, a fixed contact member closely spaced from the second flexible contact, and actuator means movable into engagement with the second flexible contact for moving the second flexible contact away from the said another stationary contact member and into conductive engagement with the first flexible contact and the fixed contact member.

6. A switch comprising a base of insulating material, a first flexible contact mounted on the base in conductive engagement with a first stationary contact member, a pair of flexible contacts mounted on the base each in conductive engagement with other stationary contact members, and actuator means selectively movable into engagement with either of the pair of flexible contacts for moving such flexible contact into conductive engagement with the first flexible contact.

7. A switch comprising a base of insulating material, a first flexible contact mounted on the base in conductive engagement with a first stationary contact member, a pair of flexible contacts each having a portion thereof fixedly mounted on the base, a pair of fixed contact members each closely spaced from either of the pair of flexible contacts, and actuator means selectively movable into engagement with either of the pair of flexible contacts for moving such contact into conductive engagement with the first flexible contact and one of the pair of fixed contact members.

8. A switch comprising a base of insulating material, a first flexible contact mounted on the base in conductive engagement with a first stationary contact member, a pair of flexible contacts mounted on the base each in rigid conductive engagement with other stationary contact members and each biased into conductive engagement with a common stationary contact, a pair of fixed contact members each closely spaced from one of the pair of flexible contacts, and actuator means selectively movable into engagement with either of the pair of flexible contacts for moving such flexible contact into conductive engagement with the first flexible contact and one of the pair of fixed contacts and for moving such flexible contact away from the common stationary contact.

9. A direction signal switch comprising a base of insulating material including integral retaining lugs on one side thereof, a plurality of contact pins projecting from the base on the same side as the retaining lugs, a C-shaped spring contact resiliently engaging a contact pin and a pair of lugs, a pair of J-shaped spring contacts each retained between a terminal pin and a lug and having a movable leg, a pair of contact pins each closely spaced from a movable leg of one of the J-shaped contacts, and an actuator member disposed between the movable legs and adapted to selectively move each of the movable legs into engagement with an end of the C-shaped contact and with one of the pair of contact pins.

10. A direction signal switch comprising a base of insulating material including integral retaining lugs on one side thereof, a plurality of contact pins projecting from the base on the same side as the retaining lugs, a C-shaped spring contact resiliently engaging a contact pin and a pair of lugs, a pair of J-shaped spring contacts each retained between a terminal pin and a lug and having a movable resilient leg closely spaced from an end of the C-shaped contact and resiliently biased toward a

common contact pin, a pair of contact pins each closely spaced from a movable leg of one of the J-shaped contacts, and an actuator member disposed between the movable legs and adapted to selectively move each of the movable legs into engagement with an end of the C-shaped contact and with one of the pair of contact pins.

11. A direction signal switch comprising a base of insulating material including integral retaining lugs on one side thereof, a plurality of contact pins projecting from the base on the same side as the retaining lugs, an electrical conductor secured to each of the contact pins, a C-shaped spring contact resiliently engaging a contact pin and a pair of lugs, a pair of J-shaped spring contacts each retained between a terminal pin and a lug and having a movable resilient leg closely spaced from an end of the C-shaped contact and resiliently biased toward a common contact pin, a pair of contact pins each closely spaced from a movable leg of one of the J-shaped contacts, a well in the base between the J-shaped contacts, and an insulated actuator member disposed in the well between the movable legs and adapted to selectively move each of the movable legs away from the common contact pin and into engagement first with an end of the C-shaped contact and subsequently with one of the pair of contact pins.
